TEMPERATURE RESPONSIVE DEVICE

Joseph M. Brian, Linthicum Heights, Md., assignor, by mesne assignments, to Bendix Aviation Corporation, South Bend, Ind., a corporation of Delaware

Application June 29, 1939, Serial No. 281,985

3 Claims. (Cl. 297—15)

This invention relates to electrical apparatus, and more particularly to thermostatically controlled condensers for compensating for the effects of temperature variation on the component elements of a tuned circuit.

In radio and allied fields which employ oscillatory currents of high frequency, the maintenance of a particular frequency is exceedingly important, and allowable frequency drift is confined to very close tolerances. One of the predominant causes of frequency drift in tuned circuits is a change in the circuit characteristics at different levels of temperature. As a tube heats, the inter-electrode capacities change values. The coils and other components are heated by radiation from the tubes and by a general rise in the ambient temperature under operating conditions, thus producing thermal expansion of the components and varying distributed capacity relations and circuit tuning generally. All of these variable factors contribute to change the frequency to which the circuit may be resonant. By good design practices such frequency shifts may be kept fairly small, but in many instances a higher degree of precision is required. In such cases a thermostatically controlled variable condenser of small capacity may be connected in the tuned circuit in such manner that its value changes in opposite sense to other changing values of the circuit, and so stabilize the overall constants of the circuit. Previous condensers of this type have generally comprised aligned parallel plates, one of which is moved toward the other by thermostatic action. One big disadvantage of such condensers is that the change of capacity is not linear with temperature and such a relation is frequently desirable in practice. Another disadvantage has been that the capacity rate of change per degree of temperature change could not readily be modified to suit changing circuit requirements. The invention to be later described offers a solution to both of the foregoing difficulties.

One object of this invention is to provide a condenser which varies in capacity in response to changes of temperature.

Another object is to provide a temperature responsive variable condenser in which the range of operation may be more easily and accurately controlled.

Another object is to provide a temperature responsive variable condenser which employs standard and readily available constituent parts.

A further object is to provide a temperature

responsive variable condenser in which the rate and degree of capacity variation with respect to temperature may be readily adjusted.

Other objects and advantages will in part be specifically stated and in part be obvious when the following specification is read in connection with the drawing, in which:

Fig. 1 is a front elevation of the invention; and Fig. 2 is a top plan view.

Referring in more detail to Fig. 1, the numeral 1 indicates a mounting base upon which a bracket 2 supports a variable condenser 3 of the interleaving plate type. The condenser may be a well known "midget" size which is commercially available and comprises a ceramic base 4 which is attached to the bracket 2 by screw fastenings 5 and 6. The stator bars 7 and 8 extend from the ceramic base and carry the stator plates 9. A rotatable shaft 10 extends through the base 4 and carries the rotor plates 11 in interleaving relation to the stator plates. As best seen in Fig. 2, a block 12 is fixed to the forward end of shaft 10, and is bored to receive the laterally extending arm 13. Adjustably mounted on the arm 13 is a collar 14. A bimetallic strip 15 has one end resting on the upper surface of the collar and a set screw 16 passes through an opening, which may be in the form of a slot, in the strip to secure the collar 14 in desired position on the arm 13. The end of the strip 15 is retained snugly against the collar by a compression spring 17 which bears against the head of the set screw 16. The other end of the bimetallic strip 15 is secured to the flattened top of a post 18 which is angularly adjustable with respect to the mounting base 1. The post 18 (Fig. 1) has a reduced shank portion 19 which passes through a spacing spool 20 and the base 1. A collar 21 is mounted on the projecting end of the shank 18 and it may be drawn up tightly and secured with the set screw 22 to hold the post 18 and bimetallic strip 15 in desired angular position.

It will be obvious that many changes and modifications may be made by anyone skilled in the art without departing from the spirit and scope of the invention as defined in the following claims.

What is claimed is:

1. In a thermally responsive device, a driven element having a rotatable shaft, an arm attached to said shaft and projecting laterally therefrom, a bimetallic strip comprising a strip of one metal secured to a strip of a dissimilar metal at a plurality of points over their common length, the interface between the two metals

defining a plane surface at a predetermined reference temperature, means for mounting said bimetallic strip with said interfacial plane substantially parallel to the axis of rotation of said shaft and for rotating said bimetallic strip about an axis substantially perpendicular to said axis of rotation of said shaft and to said interfacial plane and parallel to the plane determined by the thermally produced movement of said bimetallic strip, and means providing a driving coupling between one end of said bimetallic strip and said arm.

2. In a thermally responsive device, a driven element having a rotatable shaft, an arm attached to said shaft and projecting laterally therefrom, a bimetallic strip comprising a strip of one metal secured to a strip of a dissimilar metal at a plurality of points over their common length, the interface between the two metals defining a plane surface at a predetermined reference temperature, means for mounting said bimetallic strip with said interfacial plane substantially parallel to the axis of rotation of said shaft and for rotating said bimetallic strip about an axis substantially perpendicular to said axis of rotation of said shaft and to said interfacial

plane and parallel to the plane determined by the thermally produced movement of said bimetallic strip, and means adjustable along the length of said arm for coupling one end of said bimetallic strip in driving relation to said arm.

3. In a thermally responsive device, a driven element having a rotatable shaft, an arm attached to said shaft and extending laterally therefrom, a post angularly adjustable about an axis substantially perpendicular to the axis of rotation of said shaft and parallel to the plane of rotation of said arm, a bimetallic strip comprising a strip of one metal secured to a strip of a dissimilar metal at a plurality of points over their common length, the interface between the two metals defining a plane surface at a predetermined temperature, means for securing one end of said bimetallic strip to said post with said interfacial plane substantially parallel to the axis of rotation of said shaft and perpendicular to said axis of angular adjustment of said post, and means providing a driving connection between the other end of said bimetallic strip and said arm.

JOSEPH M. BRIAN.
